(57) **CLAIM**

The ornamental design for a “booster car seat,” as shown and described.

DESCRIPTION

FIG. 1 is a perspective view of booster car seat, showing my new design;

FIG. 2 is a front view thereof;

FIG. 3 is a back view thereof;

FIG. 4 is a right view thereof;

FIG. 5 is a left side view thereof;

FIG. 6 is a top side view thereof; and,

FIG. 7 is a bottom top view thereof.

The subject matter shown in dashed lines is for illustrative purposes and forms no part of the claimed design.
